UNITED STATES PATENT OFFICE

ROY E. PETERSON, OF EAST NORWALK, CONNECTICUT, ASSIGNOR TO THE E. H. HOTCHKISS COMPANY, OF NORWALK, CONNECTICUT, A CORPORATION OF CONNECTICUT

ROTARY ANVIL FOR STAPLING MACHINES

Application filed June 12, 1929. Serial No. 370,342.

This invention relates to stapling machines and has for an object to provide easily adjustable means for setting the staples in different manners.

- 5 It is a further object of the invention to provide an adjustable clinching means or anvil which has a means for indicating the particular type of clinching surface that is in operative position.
- 10 It is an additional object of this invention to provide a clinching means or anvil that is quickly and easily removable and replaceable in the stapling machine, whereby additional anvils having different types of clinching surfaces may be substituted at will.

With the foregoing and other objects in view, the invention consists in certain novel features of construction, combinations and arrangements of parts as will be more fully disclosed in connection with the accompanying drawings.

In the drawings

Fig. 1 is a partial side elevation and partial section showing a stapling machine having 25 my easily adjustable and removable clinching means.

Fig. 2 is a front elevation thereof.

Fig. 3 is a fragmentary front elevation partly broken away showing one type of 30 clinching surface in operation.

Fig. 4 is a similar view showing another type of clinching surface.

Fig. 5 is a partly broken fragmentary section showing the means for holding the anvil 35 with a desired surface in operative position.

Figs. 6 and 7 are front elevations of the anvil showing the different types of clinching surfaces and the indicating means thereon.

40 Fig. 8 is a section through the anvil on line 8—8 of Fig. 6.

The machine illustrated comprises the usual base 10 to which is pivoted the housing 11 as at 12. The housing carries the usual 45 vertically reciprocating plunger 13, which is operated by a knob 14 at its upper end by a blow from the hand, and is normally held in its upper position by a spring 15 either outside or within the housing as desired.

50 The staples 16 which are substantially

U-shape are preferably of wire either round or somewhat flattened and are fed in an inverted position with their prongs downwardly along the top of the guide bar 17 by means of an inverted U-shaped follower 18 55 drawn forward by a spring 19 to feed the staples successively to the position for driving under the plunger.

The base 10 carries a block 20 divided into two parts 21 by a circular groove in 60 which the rotary anvil 22 is placed for operation. A pin 23 is fitted in an opening through the block 20 and passes through an annular groove 24 in the anvil 22 and serves to retain the anvil in place, but leaves it free for rotation. If desired, the pin 23 may be removed thereby permitting the anvil 22 to be removed and replaced. On the anvil 22 are a plurality of clinching surfaces 25, 26 and 27 of 65 different types, and although only these types 70 are shown, additional types may be likewise placed thereon if desired. Depressions 28 serve as catches for the yieldable detent 29, which comprises a ball and spring, placed in the base 10 beneath the anvil. On the handle 75 portion 30 of the anvil 22 are placed indications 31 in line with the various clinching surfaces and serve to show the particular surface in operative position. Thus, at 25 is shown the light duty clinching surface indicated at 31 by the letter L, at 26 is the heavy duty surface indicated by H and at 27 the temporary duty surface at T for turning the prongs in one direction instead of opposite directions. For example the light 80 surfaces may be used with staples of thinner stock, while the heavy duty recesses may be used with staples of heavier stock. In both these arrangements the recesses are positioned to bend both prongs of the staples 85 inwardly toward each other for a permanent attaching. In the arrangement of the surfaces shown at 27 both prongs of the staples are bent in the same direction as shown in Fig. 4, that is inwardly from one side and 90 outwardly from the other. This is for more or less temporary work as a staple set this way is easier to remove than one set with both prongs bent inwardly.

In operation the articles to be stapled, such 100

as the sheets of paper 32, are placed on the block 20 over anvil 22, which has been rotated until the indication 31 shows that the desired clinching surface is in operative position, and under the forward end of the housing after raising the housing. The forward end of the housing thus rests on top of the paper, and when the plunger is depressed by a blow on knob 14 the prongs of 10 the staple are forced through the paper and ends engage in the particular clinching surface then in operative position and are set accordingly.

Having thus set forth the nature of my invention, what I claim is:

1. In a stapling machine, a base, a housing pivoted to the base, a movable plunger in the housing, means for operating the plunger, a rotatable anvil in said base having 20 a plurality of different clinching surfaces located about its longitudinal axis to cooperate with the plunger in setting staples, and means to mount said anvil with its longitudinal axis extending transversely of the 25 base and to rotate about said longitudinal axis.

2. In a stapling machine, a base, a housing pivoted to the base, a movable plunger in the housing, means for operating the 30 plunger, and a rotatable cylindrical anvil mounted in said base with its axis extending transversely of the base and also mounted to turn about its axis, said anvil having a plurality of different staple clinching surfaces 35 therein located about said axis.

3. In a stapling machine, a base, a housing pivoted to the base, a movable plunger in the housing, means for operating the plunger, a rotatable cylindrical anvil in said 40 base, said anvil having a plurality of pairs of different staple clinching surfaces therein positioned about its longitudinal axis and extending longitudinally thereof, the surfaces of each pair adapted to engage the prongs of 45 a substantially U-shaped staple and bend them in different ways, and means for rotating said anvil about said axis to place a desired pair of clinching surfaces in operative position.

4. In a stapling machine, a base, a housing pivoted to the base, a movable plunger in the housing, means for operating the plunger, an anvil extending transversely of 50 said base and rotatable about a longitudinal axis, said anvil having a plurality of different clinching surfaces therein, means for rotating said anvil to place a desired clinching surface in operative position, and means for retaining said anvil in a desired operative 55 position.

5. In a stapling machine, a base, a housing pivoted to the base, a movable plunger in the housing, means for operating the plunger, a rotatable anvil with its longitudinal axis 60 extending transversely of said base, said an-

vil having a plurality of different staple clinching surfaces therein, means indicating the particular clinching surface in operative position, means for rotating said anvil about said axis to place a desired clinching surface in operative position, and means for retaining said anvil in a desired operative 70 position.

6. In a stapling machine, a base, a housing pivoted to the base, a movable plunger in the 75 housing, a removable cylindrical anvil rotatable about its longitudinal axis extending transversely of said base, said anvil having a plurality of different staple clinching surfaces 80 therein positioned about said axis, and means for retaining said anvil in operative position.

7. In a stapling machine, a base, a housing pivoted to the base, a movable plunger in the 85 housing, means for operating the plunger, an anvil housing in said base, and a removable anvil mounted in said anvil housing to rotate about its longitudinal axis transversely of 90 said base, said anvil having a plurality of staple clinching surfaces and corresponding indications about said axis.

8. In a stapling machine, a base, a housing pivoted to the base, a movable plunger in the housing, means for operating the plunger, an anvil housing with its longitudinal axis extending transversely of said base, a rotatable anvil in said anvil housing mounted to rotate about said axis, and means for removably 95 retaining said anvil in said housing.

9. In a stapling machine, a base, a housing 100 pivoted to the base, a movable plunger in the housing, means for operating the plunger, an anvil housing in said base, a rotatable anvil mounted in said anvil housing with its longitudinal axis extending transversely of said 105 base, means for removably retaining said anvil in said housing, and means yieldably preventing said anvil from rotating.

10. In a stapling machine, a base, a housing pivoted to the base, a movable plunger in the 110 housing, means for operating the plunger, an anvil housing in said base, a rotatable anvil in said anvil housing, and means for removably retaining said anvil in said housing, said means comprising a pin opening in said anvil housing, an annular groove on said anvil, and a pin passing through said opening and into said groove.

11. In a stapling machine, a base, a housing connected to the base, a movable plunger in the housing, means for operating the plunger, a rotatable anvil in said base having a plurality of pairs of different clinching surfaces located about its longitudinal axis and extending longitudinally thereof, said 120 surfaces being adapted to cooperate with the plunger in setting the staples, and means to mount said anvil to turn about said longitudinal axis.

12. A cylindrical anvil for stapling ma- 125

chines having a plurality of pairs of different clinching surfaces in its curved wall adapted for engaging and bending in different ways the prongs of substantially U-shaped staples, 5 said surfaces being located to extend substantially longitudinally of the axis of the anvil.

13. An anvil for stapling machines adapted to be mounted to turn about a longitudinal 10 axis and having in its surface a plurality of pairs of different clinching surfaces adapted to engage and bend in different ways the prongs of substantially U-shaped staples, said surfaces being located on different sides 15 of said longitudinal axis and extending substantially longitudinally thereof.

In testimony whereof I affix my signature.
ROY E. PETERSON.
